John Stewart,
ATTORNEY.

UNITED STATES PATENT OFFICE.

MARIO CAMAGNI, OF PATERSON, NEW JERSEY.

TENSION LEVER.

Application filed April 30, 1928. Serial No. 273,852.

This invention relates to tension devices for shuttles of the class in which, with a line of fixed pins or other guides, there is a lever having a plurality of guides and normally held by an elastic in such relation to the fixed guides that the filling, reaching in alternation around the fixed guides and the guides of the lever, extends normally in zig-zag arrangement, and the object is to provide a lever 5 for a tension device of this class in which the shank and guide or guides thereof, or it may be the shank and guide or guides thereof and also the fulcrum part of the lever, may be formed from a blank of stiff sheet material— 10 thus reducing the cost of manufacture of such devices—and yet function with full efficiency in the shuttle.

In the drawing,

Fig. 1 is a plan of a shuttle, partly broken 20 away, embodying the improved tension lever;

Fig. 2 is a plan of the blank from which the lever is formed;

Fig. 3 is a side elevation of the lever in 25 partly completed form;

Fig. 4 is a plan of the completed lever;

Fig. 5 is a right hand end elevation thereof; and

Fig. 6 is a section on line 6—6, Fig. 5.

In the usual cavity 1 of the shuttle body 30 2 is a fulcruming pin 3 for the improved tension lever (designated by the character 4 in that figure), which by an elastic band 5 is normally held retracted with respect to a line of pins or thread guides 6 so that, all in a 35 well known way, the filling, which is threaded around these pins and alternately through the guides on the lever, is normally held zig-zag, the lever yielding toward the line of pins when the filling is pulled upon, as when the 40 shuttle is in action.

The said lever is formed (here completely) 45 from a blank of sheet material which comprises an elongated portion 7 and eyes 8 arranged in succession along said portion and each projecting from one long edge thereof; in the present example all the eyes project from the same long edge of the portion 7, and the material of each around the opening 9 thereof through which in the completed device the filling reeves is endless or continuous, 50 although this is not indispensable if in the completed device the several eyes as guides coact to retain the filling in them.

With the blank so formed each eye 8 is 55 twisted so that the material thereof will lie

in a plane intersecting the axis of the portion 7, as perpendicular thereto (Fig. 3).

If the eyes all project from the same long edge of the portion 7, which forms the shank for a line of guides formed by the eyes 8, the 60 forming of the filling-guiding portion of the lever (except for some preferable treatment of each eye such as that to be described) will be complete without further manipulation.

In the preferable construction the portion 65 of the eye forming each guide which is remote from the support therefor afforded by the shank is bent off and forms at the side thereof adjoining the support a guiding surface 10 for the filling, the said guiding surface 70 preferably being rounded or convex by bending said bent-off portion itself around an axis crossing the path of travel of the filling, or here the axis of the shank. The purpose is to avoid undue abrasion or cutting of the 75 filling. This I believe is a novel form of filling or thread guide independently of its adaptation to a tension lever. In the preferred form said surface extends straight and also parallel with the axis of the lever, 80 so that the filling does not tend to track in any particular portion of the surface.

It is not material how the fulcrum portion and the lever arm to which the elastic 5 is attached are formed, but in the present case instead of forming them from a separate piece of wire as in my Patent No. 990,334 I show them as formed from integral parts of the blank and substantially the same as in my application for patent for a shuttle tension 90 Serial No. 273,851, to wit: The shank-forming portion 7 is extended at one end and has opposite ribs 11 projecting therefrom, and said portion being given a quarter-turn twist, as at 7^a, these are bent off in the direction relatively opposite to the guides already described on spaced lines parallel with the axis of the shank and formed with aligned holes 12 for the bearing pin 3, the ribs thus becoming the fulcrum portion of the lever; and the 100 end 13 of said extension is provided with holes 14 and this is bent off in the same direction as the ribs 11, one of its holes then serving to receive the elastic 5 which may be knotted as shown in Fig. 1.

Having thus fully described my invention, 105 what I claim is:

1. A tension lever for a shuttle tension including a shank and a filling guide, said shank and guide being formed from a blank 110

of stiff sheet material comprising an elongated portion to form the shank and an eye projecting from one long edge thereof, said eye being twisted so that the material thereof lies in a plane intersecting the axis of the shank and the eye thus forms the guide.

2. A tension lever for a shuttle tension including a shank and a plurality of aligned filling guides, said shank and guides being formed from a blank of stiff sheet material comprising an elongated portion to form said shank and eyes arranged in succession along said portion and each projecting from one long edge thereof, each eye being twisted so that the material thereof lies in a plane intersecting the axis of the shank and thus forms one of said guides.

3. A tension lever for a shuttle tension including a shank and a plurality of aligned filling guides, said shank and guides being formed from a blank of stiff sheet material comprising an elongated portion to form said shank and eyes arranged in succession along said portion and each projecting from the same edge thereof, each eye being twisted so that the material thereof lies in a plane intersecting the axis of the shank and thus forms one of said guides.

4. A tension lever for a shuttle tension including a shank, a filling guide and a fulcrum part, said shank, guide and fulcrum part being formed from a blank of stiff sheet material comprising an elongated portion to form said shank, an eye projecting from one long edge thereof, and a pair of apertured ribs projecting from the respective long edges of said portion, said eye being twisted so that

the material lies in a plane intersecting the axis of said portion and thus forms the guide, and said ribs being bent off both in the same direction and thus forming the fulcrum part.

5. A tension lever for a shuttle tension including a shank, a filling guide and a fulcrum part, said shank, guide and fulcrum part being formed from a blank of stiff sheet material comprising an elongated portion to form said shank, an eye projecting from one long edge thereof, and a pair of apertured ribs projecting from the respective long edges of said portion, said eye being twisted so that the material lies in a plane intersecting the axis of said portion and thus forms the guide, the material of said portion being twisted between the guide and said ribs and the latter being bent off both in the same direction and thus forming the fulcrum part.

6. A sheet metal guiding device for a shuttle comprising a support and an eye projecting from one edge thereof, the portion of the eye remote from the support being bent off and having the surface of such bent-off portion relatively adjoining the support forming the filling guiding surface of the eye.

7. A sheet metal guiding device for a shuttle comprising a support and an eye projecting from one edge thereof, the portion of the eye remote from the support being bent off and having the surface of such bent-off portion relatively adjoining the support forming the filling guiding surface of the eye, and said surface being convex around an axis crossing the path of travel of the filling.

In testimony whereof I affix my signature.
MARIO CAMAGNI.
